(57) **CLAIM**

The ornamental design for a garden tool, as shown and described.

DESCRIPTION

FIG. 1 is a front top perspective view of a garden tool in the present invention.

FIG. 2 is a rear bottom perspective view thereof.

FIG. 3 is a front view thereof.

FIG. 4 is a rear view thereof.

FIG. 5 is a top view thereof.

FIG. 6 is a bottom view thereof.

FIG. 7 is a right side view thereof.

FIG. 8 is a left side view thereof.

FIG. 9 is a cross sectional view of the garden tool taken along lines 9-9 in FIG. 8; and,

FIG. 10 is an enlarged cross sectional view of the handle of the garden tool taken from indication circle 10 of FIG. 9. The broken lines in the drawings illustrate portions of the garden tool and form no part of the claimed design.

The dot-dash-dot broken lines showing in FIGS. 9 and 10 illustrate indication circles and form no part of the design.
